UNITED STATES PATENT OFFICE

JOHN MERRY, OF NEW YORK, N. Y., ASSIGNOR TO THE BIGELOW CARPET COMPANY, OF MASSACHUSETTS.

DESIGN FOR A RUG.

SPECIFICATION forming part of Design No. 30,510, dated April 4, 1899.

Application filed March 10, 1899. Serial No. 708,603. Term of patent 3½ years.

To all whom it may concern:

Be it known that I, JOHN MERRY, a subject of the Queen of Great Britain, and a resident of the city, county, and State of New York, 5 have invented a new and original Design for Rugs, of which the following is a specification.

My design, as shown in the drawing, consists in a new design for a rug.

10 The design is composed of a central portion and a border. The central portion is rectangular in shape, inclosing an octagon produced by the location of triangular ornamental figures at each corner of the rectangle. The 15 border is composed of a broad stripe having both on its outer and its inner margin a narrow stripe and having also a bold ornamental rug-like figure at each corner. Small rug-like figures are loosely distributed outside of the 20 border proper. The inner stripe of the bor-

der forms the boundary of the rectangular center portion of the rug.

The rug as a whole is profusely ornamented with picturesque shapes and conventional geometrical outlines distinctly suggestive of 25 the characteristic figuring of oriental rugs.

The design shows one quarter of the design, the remaining three quarters being in all respects facsimiles thereof.

What I claim as new, and desire to secure 30 by Letters Patent, is—

The design for a rug, substantially as shown and described.

In testimony whereof I have signed my name to this specification in the presence of 35 two subscribing witnesses.

JOHN MERRY.
